OF ELIZABETH, NEW JERSEY, A CORPORATION OF NEW JERSEY.

COUNTERBALANCE DEVICE FOR MOLDING-MACHINES.

1,299,412.

Specification of Letters Patent.

Patented Apr. 8, 1919.

Application filed March 1, 1917. Serial No. 151,641.

To all whom it may concern:

Be it known that I, ABBOTT ALLEN, a citizen of the United States, and residing at Dunellen, in the county of Middlesex and 5 State of New Jersey, have invented certain new and useful Improvements in Counterbalance Devices for Molding-Machines, of which the following is a specification.

This invention relates to a counterbalance device for molding machines, particularly 10 that type of molding machine in which there is a trunnioned ramming yoke against which the mold to be rammed is squeezed, such for example as in plain power squeezers, combination jolt and squeeze machines, and split pattern machines or combinations thereof.

It has for one of its primary objects the provision of a simple, compact, economical and effective counterbalance means whereby 20 the manipulation of the ramming yoke is rendered easy and expeditious.

The foregoing, together with such other objects as may hereinafter appear, or are incident to the invention, are attained by 25 means of a construction, the preferred form of which is illustrated in the accompanying drawings, wherein—

Figure 1 is a front elevation and partial section of a plain power squeezer showing 30 the invention applied thereto, and Fig. 2 is an end elevation and partial section of the machine shown in Fig. 1.

The plain power squeezer shown in the drawings comprises a hollow base casting 7 35 mounted upon which is a cylinder 8 in which works a plunger 9 provided with a mold table 10 at its top. A transverse shaft 11 is mounted in the base 7, and pinned to the ends of the shaft by means of the pins 12 40 are two tubular side rods 13 which, in conjunction with the strain bar 14, constitute a ramming yoke which in operative position occupies the position shown in full lines in Figs. 1 and 2, and in inoperative position, 45 the position indicated in dotted lines in Fig. 2.

The ramming yoke is provided with a ramming block or platen 15 against which the sand in the flask or flasks mounted on 50 the mold table 10 is compressed or squeezed by means of the introduction of fluid pressure such as air beneath the plunger 9 which effects the elevation of the plunger and the parts carried thereby toward the platen. At 55 extremes of movement the ramming yoke

comes against the stops 16 and 17 (see Fig. 2).

The operation of the machine thus far described is as follows, assuming that the ramming yoke occupies the dotted line position. 60 The flask or flasks being in position upon the mold table 10, and being filled with sand, the ramming yoke is swung until it occupies the full line position, whereupon air is introduced beneath the plunger 9 in the usual 65 manner (by means not shown), and the mold parts are advanced toward the platen 15 and the sand is tightly squeezed or rammed, forming the proper mold cavities in the sand. The air is then exhausted, the ramming yoke swung to the dotted line position 70 and the mold removed, when the machine is ready for another operation.

The ramming yoke is manipulated by hand, and since it is quite heavy, it is desirable to provide counterbalance means to render the manipulation of the ramming yoke easy. This is not the first instance in 75 the molding machine art in which counterbalance means have been provided, and the 80 invention resides in improvements over the customary counterbalance means employed. Such means will now be described.

Mounted upon the shaft 11, within the base casting 7, at spaced intervals, are two 85 collars 18, each of which is secured in place by means of a pin 19 and is provided with a downwardly depending nose 20 adapted to be pivotally supported in the cleaved end 21 of a cup-shaped member 22. A compression spring 23 is supported between each cup-shaped member 22 and a similar member 24, the spring being positioned with respect to said members by means of the central bosses 26. The cup-shaped members 24 90 are loosely engaged by adjusting studs 25 threaded into the wall of the base casting 7, and are held in position over the ends of said studs by means of the springs 23. The studs 25 perform the double function of assisting in positioning the cups 24 and in varying the amount of pressure exerted by the springs 23. 95

Assuming that the ramming yoke is in the full line position, when it is swung to the 100 dotted line position, the noses 20 will of course be swung around, but since they are offset with respect to the center line of the shaft 11, and since the cups 22 are pivotally mounted thereon, it will be apparent that 110

the springs 23 will not be materially shifted out of the plane in which they extend when the ramming yoke is in full line position, although of course they will be under compression. The advantage of this arrangement will be obvious. In the first place, it is unnecessary to increase the size of the base casting, as would be the case were the springs to be shifted materially. In the next place, both the cups 22 and 24 accommodate themselves to the change in position of the parts so that the springs are at all times adequately supported and uniformly compressed. It is preferred that the springs be so adjusted that when in full line position, the ramming yoke is lightly held in position against the stop 16, while when in dotted line position, the weight of the ramming yoke is just sufficient to cause the ramming yoke to lie against the stop 17, that is to say, the weight of the parts is just sufficient to overcome the pressure exerted by the compression springs. This makes the ramming yoke easy to manipulate.

25 I claim:—

1. In a molding machine, the combination of a base, a shaft trunnioned therein, a ramming yoke mounted on said shaft, a pair of spaced downwardly depending arm-like members on said shaft within the base, and a counterbalance compression spring engaging each of said members and mounted within the base and interposed between the base and each of said members.

35 2. In a molding machine, the combination of a base, a shaft trunnioned therein, a ramming yoke carried by said shaft, two spaced, downwardly extending arms on said shaft, a spring-engaging member pivotally mounted on each arm, and a compression spring adapted to engage each spring-engaging member.

45 3. In a molding machine, the combination of a base, a shaft trunnioned therein, a ramming yoke carried by said shaft, two spaced, downwardly extending arms on said shaft, a spring-engaging member pivotally mounted on each arm, a second pair of spring-engaging members supported in the base in alinement with the first pair of spring-engaging members, and a compression spring between each pair of members.

50 4. In a molding machine, the combination

of a base, a shaft trunnioned therein, a ramming yoke carried by said shaft, two spaced, downwardly extending arms on said shaft, a spring-engaging member pivotally mounted on each arm, a second pair of spring-engaging members loosely supported in the base in alinement with the first pair of spring-engaging members, and a compression spring between each pair of members.

5. In a molding machine, the combination of a base, a shaft trunnioned in the base, a ramming yoke mounted on the shaft, an offset downwardly projecting arm on said shaft, a spring-engaging member pivotally mounted on said arm, and a compression spring adapted to engage said member.

6. In a molding machine, the combination of a base, a shaft trunnioned in the base, a ramming yoke mounted on the shaft, an offset downwardly projecting arm on said shaft, a spring-engaging member pivotally mounted on said arm, a second spring-engaging member supported in the base, and a compression spring between said members.

7. In a molding machine, the combination of a base, a shaft trunnioned in the base, a ramming yoke mounted on the shaft, an offset downwardly projecting arm on said shaft, a spring-engaging member pivotally mounted on said arm, a second spring-engaging member supported in the base, and a compression spring between said members, together with means for altering the compression of said spring.

8. In a molding machine, the combination of a base, a shaft trunnioned in said base, a ramming yoke mounted on said shaft, a pair of collars non-rotatively mounted on said shaft at spaced intervals, each collar being provided with a downwardly extending arm offset with respect to the center line of the shaft, a cup-shaped spring-engaging member pivotally mounted on each arm, a second cup-shaped member in opposition to each of the aforesaid cup-shaped members, a compression spring between each pair of cup-shaped members, and means whereby the second pair of cup-shaped members are loosely supported in the base.

In testimony whereof I have hereunto signed my name.

ABBOTT ALLEN.
